UNITED STATES PATENT OFFICE

GEORGE O. RUFF, OF PARIS, ILLINOIS

FIRE EXTINGUISHING GRENADE HOLDER

Application filed October 27, 1930. Serial No. 491,577.

The invention relates to improvements in holders for fragile grenades adapted to shatter and release a fire extinguishing fluid, when allowed to drop by melting of a fusible element.

It is the principal object of the invention to provide an exceptionally simple and inexpensive, yet an efficient and reliable holder for the grenade, which holder may if desired be constructed entirely from thin sheet metal.

A further object of the invention is to make novel provision for completing an alarm circuit when the fusible element melts and the grenade falls.

15 A still further aim is the provision of unique and advantageous fusible means for normally holding the grenade engaged with its support.

20 With the foregoing in view, the invention resides in the novel subject matter hereinafter described and claimed, description being accomplished by reference to the accompanying drawings.

Fig. 1 is a front elevation.

25 Fig. 2 is a perspective view.

Fig. 3 is a vertical sectional view on line 3—3 of Fig. 1.

30 Fig. 4 is a vertical section on line 4—4 of Fig. 3.

Figs. 5 and 6 are detail sectional views on the correspondingly numbered lines of Fig. 2.

Fig. 7 is an elevation of the sheet metal blank from which the support is formed.

35 Fig. 8 is a disassembled perspective view of the two pivoted arms which are connected by a fusible element.

Fig. 9 is an enlarged horizontal sectional view through the connected ends of the above mentioned arms.

40 Fig. 10 is a vertical transverse sectional view on line 10—10 of Fig. 9.

A preferred construction has been illustrated and will be specifically described, with the understanding however that within the 45 scope of the invention as claimed, variations may be made.

The device is in the nature of a bracket B embodying a horizontal top plate 12, a vertical back plate 13, and two side plates 14 connected with the vertical edges of said back

plate and with the longitudinal edges of said top plate. The top plate 12 is of U-shape, being provided with a recess 15 between its arms 16, which recess is adapted to receive the vertical neck 17 of the grenade 18. Below the top plate 12 a horizontal brace plate 19 projects forwardly from the back plate 13 and is provided with a concave front end or seat 20 to engage neck 17.

Two vertical lugs 21 project downwardly from the front ends of the arms 16, two additional vertical lugs 22 project inwardly from the front ends of the side plates 14 and are spaced in advance of said lugs 21, and two bracing lugs 23 project inwardly from said side plates 14 and are snugly positioned in the angles between these plates and the top plate 12. Front-to-rear pivot screws or other pins 24 pass through all of the lugs 21, 22 and 23, said pins being threaded into the lugs 23 in the present disclosure and having heads 25 abutting the lugs 22.

Two horizontal arms 26 are connected with each other in overlapped relation by a fusible element 27, said arms jointly extending across the open front end of the top plate 12 to normally hold the grenade neck in the recess 15. The outer ends of these arms are received between the lugs 21 and 22 and are loosely pivoted upon the pins 24. Thus, as soon as the element 27 melts, both arms 26 drop by gravity to downwardly swung position, thereby freeing the grenade 18 and allowing it to fall and shatter, releasing the fire extinguishing fluid.

The arms 26 are preferably of acid and rust-resisting metal, bent into the shape shown most clearly in Figs. 2 and 8. The overlapped ends 28 of these arms are thinned so that they will more rapidly absorb heat, and said ends are formed with registering slots 29 preferably having enlarged ends 30. The fusible element 27 passes through these slots and is upset at 27' to retain it in place.

Passing through and insulated from one of the lugs 21, is a binding post 31 having a contact 32 at its front end, said contact being disposed between said lug 21 and the forwardly spaced lugs 22. The facing sides 100

of these two lugs are preferably provided with insulators 33 and 34.

The contact 32 is in the downward path of the overlying arm 26, so that when this arm swings downwardly upon fusing of the element 27, said arm will strike said contact. Such engagement of arm and contact is utilized to complete an electric circuit through wiring and an alarm, as illustrated in Fig. 1, 10 the top plate or other metallic part of the bracket B being provided with a binding post 35 for one of the wires. It will thus be seen that as soon as the device releases the grenade, it also completes an alarm circuit 15 so that attention is immediately called to the fire and steps may be taken to prevent possible spreading thereof.

The entire bracket B is preferably formed from a single sheet metal blank, as shown 20 in Fig. 7. The portions of the blank which form the various parts of the bracket are identified by placing thereon the same reference numbers as those used on said parts. It will be observed that the lugs 23 are 25 stamped from the side plates 14 and that the plate 19 is stamped from the back plate 13. The upper corners of the opening 36 formed by such stamping of the plate 19, are adapted to receive screws or the like to secure 30 the bracket against a wall or other support. The back plate and the side plates 13 and 14 respectively, are integral with the top plate 12, said side plates are provided with flanges 37 lying against the front of the back plate 35 13, and said flanges and back plate may be secured together by tongues 38 on the former, passing through slots 39 in the latter.

It will be seen from the foregoing that an unusually simple and inexpensive device has 40 been provided, yet one which will be highly efficient and advantageous from all standpoints. On account of such advantages, the details disclosed are preferable. Attention however is again invited to the fact that 45 within the scope of the invention as claimed, variations may be made.

I claim:—

1. A fire extinguishing grenade holder comprising a horizontally disposed U-shaped 50 inherently rigid member to embrace the neck of the grenade but incapable of alone supporting the latter, two arms loosely pivoted to the arms of said U-shaped member respectively and jointly extending across the open 55 end of said U-shaped member, and a fusible connection between said arms holding the latter across said open end of said U-shaped member, said arms and said fusible connection co-acting with said U-shaped member 60 to support the grenade, both of said arms being adapted to swing downwardly by gravity upon melting of said fusible connection, thereby releasing the grenade.

2. A fire extinguishing grenade holder 65 comprising a bracket embodying a horizontal

U-shaped top plate, two parallel side plates projecting downwardly from the longitudinal edges of said top plate, lugs projecting downwardly from the front ends of the arms of said top plate, additional lugs projecting laterally inward from the front ends of said side plates and disposed in spaced parallel relation with the first named lugs, two downwardly swingable arms disposed between the first named and additional lugs, horizontal pivot pins for said downwardly swingable arms passing through the latter and through all of said lugs, said downwardly swingable arms jointly extending across the open end of said U-shaped top plate and co-operating with the latter to support a grenade, and a fusible connection between said downwardly swingable arms holding the latter across said open end of said U-shaped plate, the latter being incapable of alone supporting the grenade, whereby upon fusing of said fusible connection and dropping of said downwardly swingable arms, the grenade will be released.

3. A structure as specified in claim 2; together with bracing lugs spaced behind the aforesaid lugs and disposed in the angles between said top and side plates, said pivot pins being passed also through said bracing lugs.

4. A fire extinguishing grenade holder comprising an inherently rigid U-shaped horizontal rigidly supported member to embrace the neck of the grenade but incapable of alone supporting the latter, a brace member below said U-shaped member having a concave seat at its front end to engage the grenade neck, means holding said U-shaped member and said brace member in fixed relation, and a closure extending across the open end of said U-shaped member and connected with the ends of the U, said closure being co-operable with said U-shaped member in supporting a grenade, said closure having a fusible portion for rendering it inoperative when fused, whereby the grenade will be released.

5. A fire extinguishing grenade holder comprising a bracket having a back plate and a U-shaped top plate, the latter being rigid with and projecting forwardly from the upper end of said back plate, said top plate being adapted to embrace the neck of a grenade but being incapable of alone supporting the latter, a grenade brace plate projecting forwardly from said back plate below said top plate and having a concave front end to engage the grenade neck, and a closure across the open end of said U-shaped top plate and connected with the ends of the U, said closure being co-operable with said top plate to support the grenade, said closure having a fusible portion for rendering it inoperative when fused, whereby the grenade will be released.

6. A structure as specified in claim 1; together with a contact in the downward path of one of the downwardly swingable arms

and adapted to be struck thereby, and a normally open alarm circuit embodying said one arm and said contact and completed by engagement of the former with the latter.

- 5 7. A structure as specified in claim 2; together with a contact carried by one of the rearmost of said lugs, said contact being disposed in the downward path of one of said downwardly swingable arms and being
10 adapted to be engaged by the latter, and a normally open alarm circuit embodying said one downwardly swingable arm and said contact and completed by engagement of the former with the latter.

- 15 In testimony whereof I affix my signature.
GEORGE O. RUFF.
